UNITED STATES PATENT OFFICE.

FREDERIC W. PHIPPS, OF WELLESLEY, MASSACHUSETTS.

GAME APPARATUS.

1,109,543.

Specification of Letters Patent.

Patented Sept. 1, 1914.

Application filed March 31, 1913. Serial No. 757,772.

To all whom it may concern:

Be it known that I, FREDERIC W. PHIPPS, a citizen of the United States, and a resident of Wellesley, in the county of Middlesex and State of Massachusetts, have invented certain new and useful Improvements in Game Apparatus, of which the following is a specification.

This invention relates to playing cards used in games, such as auction bridge, by a plurality of groups of players at a series of tables or stations, each equipped with a pack of cards, the game requiring a movement of players from table to table throughout the series.

The invention has for its object to enable the seriality, succession, or sequence of the tables to be indicated by the packs of cards thereon, so that players moving from any table may locate the next table of the series by the pack of cards on that table, instead of by independent tickets or labels as heretofore.

The invention consists in a game apparatus consisting of a series of packs of playing cards serially designated to distinguish each pack from the others, so that when the packs are distributed on card tables the seriality of the tables is indicated by the cards.

Of the accompanying drawings:—Figure 1 represents a series of packs of cards serially designated in accordance with my invention by Arabic numerals. Fig. 2 represents a series of packs serially designated by words. Fig. 3 represents a series of packs serially designated by letters. Fig. 4 represents a series of packs serially designated by Roman numerals.

The packs are shown in perspective in each figure. Any desired number of packs may be employed, the number of packs corresponding to the number of tables and players. The serial designations are preferably printed on the backs of the cards, each card of the pack bearing the same designation and the designation marks on the cards of each pack differing from those on all the other packs.

In the embodiment of the invention shown by Fig. 1 each card of the first pack bears

the numeral "1," each card of the second pack the numeral "2" and so on to the end of the series. The first pack of the series is to be placed on table number one, the second on table number two, and so on.

55

The employment of a series of packs serially designated in accordance with my invention, obviates the necessity of placing independent designating labels or tickets on card tables employed in playing progressive games. These labels are liable to be displaced by the players and lost, the result being confusion and annoyance. Moreover, a loose label on a small card table occupies space required for the fall of the cards. The preparation and care of a set of serially designated independent labels involves a considerable expenditure of time. These, and all other objections to independent labels, are obviated by my invention which 70 enables any member of a pack of playing cards to serve as a label, the pack therefore having two functions. In case a card of any pack becomes remotely separated from the body of the pack, the designating number facilitates its restoration.

75
What I claim and desire to secure by Letters Patent is:—

1. A game apparatus consisting of a series of packs of cards serially designated to 80 distinguish each pack from the others, whereby the seriality of a corresponding number of game tables or stations may be indicated, all of the members of each pack bearing the same designation.

85
2. A game apparatus consisting of a series of packs of cards serially designated, the members of each pack bearing the same serial designation, all the members of each pack bearing the same designation, and the 90 designation on the members of each pack differing from the designations on the members of the other packs.

In testimony whereof I have affixed my signature, in presence of two witnesses.

FREDERIC W. PHIPPS.
